UNITED STATES PATENT OFFICE

WILLIAM H. HARRISON, OF NEWARK, NEW JERSEY.

DESIGN FOR SHADE-ROLLER CATCH.

Specification forming part of Design No. **11,309**, dated July 29, 1879; application filed April 28, 1879.
[Term of patent 14 years.]

To all whom it may concern:

Be it known that I, WILLIAM H. HARRISON, of Newark, Essex county, New Jersey, have originated and designed a new and useful Shape for a Catch for Spring Shade-Rollers, of which the following is a full, clear, and exact description, reference being had to the annexed drawing, making part of this specification.

The drawing represents an end view of my design.

My design relates to the configuration of a catching device for the rollers of window-shades, arranged in *alto-rilievo* on the surface of a disk, as will be understood by the following description and the annexed drawing.

A is a circular disk surrounded by a raised

annular portion, B. Inside of the portion B, and raised on the surface of the disk A, are parallel guides or bars *b b b b*, four in number, between which are angular plates *c c*. Between the ends of the bars or guides *b b b b* is interposed the spindle *a*, having notches *d d* in its opposite sides.

What I claim as my invention is—

The design for a shade-roller catching device, consisting of the disk A, having arranged on its face the parallel bars or guides *b b b b* and angular plates *c c*, with the spindle *a*, presenting the notches *d d*, formed substantially as described.

WILLIAM H. HARRISON.
